PACKAGE WRAPPING

Frank L. Eddens, Birmingham, Ala.

Application October 28, 1938, Serial No. 237,402

3 Claims. (Cl. 206—41.1)

My invention relates to a novel package wrapper designed to permit the wrapping to be progressively torn away to expose the contents of the package for ready removal as needed.

5 My invention is applicable more particularly to food, confection and tobacco packages in which, as the contents are used or consumed, it is desirable to gradually tear away or open up the wrapper and yet to leave it in such form that it will 10 provide an adequate protection at all times for the residue of the package contents. It is important, in any invention of this character, that it should be designed so that it will not interfere with the use of machine packaging but will lend 15 itself to such quantity production methods, and to this end my invention, in its broadest aspect, contemplates providing for the package contents a wrapper which is formed from a blank scored or weakened lengthwise of, and preferably along 20 parallel lines corresponding to the longitudinal corners of the wrapped article or product, it being contemplated that the scored wrapper shall be folded in the manner usual and customary with all unscored or unweakened wrappings for the 25 corresponding articles.

In the utilization of my wrapper, the package is opened in the customary manner at one end and then the wrapper is torn away along the longitudinal score lines to expose the product 30 and at the same time to define flaps which are left available for folding about the exposed end of the partly consumed product.

As applied to products such as cheese, butter, bread and the like, one of the principal advantages of my invention is that the bottom section of the wrapper remains in position to furnish a sanitary apron upon which the food product rests while being cut and handled as portions thereof are removed. Under such conditions the side 40 and top flaps are drawn back as they are torn away along the score lines but the bottom is left undisturbed on the table or other support.

Another embodiment of importance applies to packaging loose goods such as smoking tobacco 45 in which the tobacco itself is enclosed in a wrapper of paper foil or the like and inserted in a metal or cardboard can or jacket.

My invention, as applied to this use, contemplates scoring or weakening the inside wrapper 50 opposite the corners of the outer can or jacket and in use, as the paper wrapper so torn along these score lines, the resultant front and end flaps are folded over outwardly so as to form suspension means for the partly consumed pack- 55 age that will present its diminishing contents

always in convenient position, while the back flap is left long enough to form a protecting cover which can be folded down over the open top of the package and held in place by closing of the top down on it.

5 My invention is obviously susceptible of a variety of embodiments and applications which will be sufficiently illustrated by the showing on the accompanying drawing which forms a part of this specification, and in which

10 Fig. 1 is a blank for a paper wrapper for a package of smoking tobacco, and

Fig. 2 shows the partly consumed package held suspended in the can by its torn flaps;

15 Fig. 3 is an enlarged cross-sectional view taken along the line III—III of Fig. 2, and showing the can top in closed position.

Similar reference numerals refer to similar parts throughout the drawing.

According to the embodiment of my invention 20 illustrated in Figs. 1 to 3, I show conventionally a metallic can 6, having a hinged top 7 with a marginal lip or flange 8, adapted to receive a paper package filled with smoking tobacco or like 25 contents, not shown. The tobacco is customarily wrapped in a waxed paper, foil or Cellophane wrapping, and in accordance with my invention I have shown such a wrapper blank 9, which may be of any desired material and which is shown formed with four parallel score lines 10, 11, 12 30 and 13, which are disposed so that they will respectively fall opposite the corners of the can when the complete tobacco package is assembled.

It is to be understood that the tobacco will be 35 packaged by machinery in the customary manner and that the finished paper or foil package with its ends folded in will be slipped into the can or outside jacket in which the package will be marketed. When the customer breaks and 40 opens the original package, he will open up the top folds of the wrapper in the usual manner and then, by pressing outwardly on the panels lying between the score lines 10, 11 and 12, 13, end flaps 14 are torn out and folded down over the 45 ends of the can, as seen in Fig. 2. This leaves front and back flaps 15 and 16, the former being folded down over the front of the can and the latter being left upstanding. When the top cover is closed it furnishes a cutting edge against which 50 the exposed portion of the flap 15 can be torn away and if desired also the exposed portion of the end flaps 14 may be torn away. The dotted line in Fig. 1 shows the original length of the flap 15 and the full line shows its torn position, 55

which corresponds substantially to the depth of the cover flange 8. I thus form a hanger lip on the front and at each end by means of which the tobacco package is suspended in the can, the 5 cover gripping these suspension flap elements to hold the package securely in suspension and at the same time they form a very effective air tight seal for the cover which presses the back flap 16 down over the tobacco to further protect it, 10 thus effectively retaining its moisture, which is a desideratum.

As the contents of the package is consumed, it is from time to time lifted higher in the can, the end flaps 14 are progressively torn out by 15 pressure outwardly between the score lines and the tearing away of the flaps proceeds until the contents of the package is consumed, the package at all times being adequately protected and firmly suspended in the can or jacket. When 20 the package is opened for use, the end, back and front flaps are all in convenient position to be engaged by the fingers when shaking the tobacco out of the can, thus enabling the user to grip and hold the package against falling outwardly 25 from, or becoming displaced in, the can or jacket.

The paper or other substance used for the package wrapper is tough enough to stand the frictional engagement of the top flange in opening and closing against the flaps the few times that it will be opened or closed for any given 30 position of the package in the can.

While my invention, as applied to loose bulk articles, has been described in connection with tobacco, it will be obvious that it has a variety 35 of applications, and if it is of particular interest to seal the packaged product against moisture, the back flap 16 can be left long enough so as to fold outwardly and be torn off even with the edge of the front top flange so that the latter

will hold the back flap in sealed position over the contents in the package.

While I have shown my invention in but one form, it will be obvious to those skilled in the art that it is not so limited, but is susceptible 5 of various other changes and modifications, without departing from the spirit thereof, and I desire, therefore, that only such limitations shall be placed thereupon as are imposed by the prior art or as are specifically set forth in the ap- 10 pended claims.

What I claim is:

1. A package for loose bulk articles of consumption, comprising an external rigid jacket having an openable flanged cover and a loose 15 container shaped to fit within the jacket and formed with score lines parallel with and adjacent to the jacket corners to subdivide the container vertically into panels adapted to be torn apart and their freed upper ends folded outwardly over the top of the ends and front side of the jacket to provide a plurality of loose suspension elements adapted, when crimped to position by closing the top, to present the container in conveniently accessible position for its con- 20 tents to be removed.

2. A package for loose bulk articles according to claim 1, in which the jacket is of the flat type with outwardly curved ends and the curved end panels of the container are adapted to have their 30 conformation reversed when folded down over the jacket ends thereby to provide a more secure support for the container.

3. A package for loose bulk articles according to claim 1, in which the panel on the back side 35 is adapted to have its free upper end folded over forwardly to form an inner protective cover for the container contents.

FRANK L. EDDENS.
